CLAIM

The ornamental design for a combined portable hand held terminal and removable carrier strap, as shown and described.

DESCRIPTION

FIG. 1 is a top right frontal perspective view of the combined portable hand held terminal and removable carrier strap showing my new design;

FIG. 2 is a bottom left frontal perspective view of the terminal;

FIG. 3 is a bottom left rear perspective view of the terminal with a removable carrier strap and strap attachment apparatus;

FIG. 4 is a side elevational view of the terminal on an enlarged scale;

FIG. 5 is a frontal view of the terminal;

FIG. 6 is a rear view of the terminal; and,

FIG. 7 is a rear view of the terminal with a removable carrier strap as illustrated in FIG. 3.

The shading shown on the strap in the figures represents a conventional fabric.
